CLAIM

The ornamental design for a stackable storage tray, as shown and described.

DESCRIPTION

FIG. 1 is a top perspective view of the stackable storage tray in accordance with my new design;

FIG. 2 is a right view thereof;

FIG. 3 is a left view thereof;

FIG. 4 is a front view thereof;

FIG. 5 is a back view thereof;

FIG. 6 is a top view thereof; and,

FIG. 7 is a bottom view thereof.

The broken lines in the drawings depict portions of the stackable storage tray which form no part of the claimed design.
